UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

MEANS FOR REMOVAL OF SMOKE FROM COKE OVENS

Application filed June 27, 1925. Serial No. 40,067.

This invention comprehends improvements of general utility in the art of charging coke ovens and similar heat treating devices, and in its more specific aspects relates to means 5 and methods for expeditiously charging coke ovens such, for instance, as those disclosed in patents to Koppers—818,033, April 17, 1906, and Becker—1,374,546, April 12, 1921, or similar constructions with the elimination 10 of the smoke nuisance during the charging operation.

In charging heat treating devices of the character indicated where a relatively long and narrow oven is employed provided with 15 a plurality of feed openings distributed along its top and smoke and gas offtakes at its ends the charges descending through the feed openings temporarily form, as it were, walls or curtains across the top of the oven interfering with the free flow of the gas generated by the coking operation and the smoke resulting from the charging operation, the gas and smoke collecting in the pockets between the successive feed openings and tending to 20 blow out therethrough, vitiating the atmosphere to such a degree as frequently to fall under the ban of local regulations. Where pipes are passed through the oven top into the pockets to take off the smoke externally 25 of the oven an elaborate system of pipes and bends is necessitated and the raising and lowering of the pipes and connecting and disconnecting them involve many difficulties. Moreover, the pipes are liable to burn out 30 and explosions are liable to occur. The pipes also become fouled by carbon and other deposits. Moreover, the external system, by reason of the length and bends in the piping necessitates the maintenance of a higher suction 35 resulting in great friction losses in removing the gases and smoke.

My invention contemplates, broadly, control of the gases within the hot ovens themselves without the necessity of using cumbersome external mechanism of any character and without the use of metal pipes or other parts liable to be burnt out. This I accomplish by providing a path of flow along the top of the oven and preferably in a substantially straight line past or through the

curtain of material descending through the feed openings during the charging operation, thus also obviating any substantial resistance to flow and friction losses incident to the taking off of the smoke through devious paths. 55 this pathway further lies throughout in brick-work and is therefore not subject to burning out by the oven heat.

Important features of my invention, in its more specific aspect, comprise a bridge member 60 made preferably of refractory material and preferably located across the bottom of the feed opening longitudinally of the oven, the bridge being provided preferably on its under side and longitudinally thereof with a 65 tunnel or gas passageway open at the bottom and extending along the top of the oven to points beyond the angle of repose of the material fed through the feed opening. The feed opening itself is preferably bellied out 70 around the bridge member so as to preserve its cross-sectional area. The bridge provides a passageway substantially on the level with the oven top through the descending material. In order to brace the bridge member 75 supporting lugs or blocks of similar material may be provided between its central part and the respective adjacent walls of the feed opening, and in order to provide for the cleaning out of the passageway the bridge 80 may be provided with cleanout openings through its crown normally closed by plugs of refractory material which may be removed through the feed opening to facilitate burning 85 out of the passageway.

In addition to the general features and objects of the invention above recited, the invention has such other improvements and advantages in construction and operation as are found to obtain in the structure and devices hereinafter described or claimed.

In the accompanying drawings, forming a part of this specification, and showing for purposes of exemplification, a preferred form 95 and manner in which the invention may be embodied or practiced, but without limiting the claimed invention specifically to such illustrative instance or instances:

Figure 1 is a cross-section of the battery on 100

the line 1—1 of Fig. 2, showing the bridge member in longitudinal section.

Fig. 2 is a section taken longitudinally of the battery on the line 2—2 of Fig. 1, showing the bridge members of two adjacent oven chambers in transverse section,

Fig. 3 is an enlarged detail view taken on line 3—3 of Fig. 4, showing a feed opening and bridge in transverse section,

10 Fig. 4 is an enlarged detail of the feed opening and bridge in longitudinal section taken on the line 4—4 of Fig. 3, and

15 Fig. 5 is an enlarged detail in horizontal section of the feed opening and bridge taken on the line 5—5 of Fig. 4.

The same characters of reference indicate the same parts in each of the several views of the drawings.

Referring to Fig. 1 there is shown the top 20 1 of a coke oven having a coking chamber 2. Feed openings 3 are provided in the top through which the fuel is fed into the oven and at the ends smoke and gas oftakes 4 are located. Located at the lower end of each 25 feed opening is a bridge member 10 spanning said opening longitudinally of the oven and provided on its under side and longitudinally thereof with a tunnel or passageway 11 extending to points on the respective sides of 30 the opening beyond the angle of repose of the material fed through said opening, such angle of repose being indicated in Fig. 1 by the dotted lines 12. The bridge member is preferably made of refractory material and 35 may conveniently be composed of bricks similar to those employed in the top wall, being preferably built integral therewith. It is also preferably provided with side lugs or extensions 14 between its central portion and the 40 respective side walls of the feed opening to constitute a brace for itself. The bridge member is also preferably provided with cleanout openings normally closed by the plugs 15 which may be removed through the top end 45 of the feed opening. The feed opening is bellied out at 16 around said bridge member and is elongated at its bottom as shown at 17 to maintain or increase its cross-sectional area in the region of the bridging members and 50 the bracing lugs or extensions therefrom.

In the operation of the device, when it is desired to charge an oven, the material is fed through the feed openings 3 passing down around the bridge members 10 and their bracing members 14 through the enlarged lower 55 ends of the openings adjacent these members and finally taking a position of repose indicated by the dotted lines 12 in Fig. 1, thus forming curtains or walls of material across 60 the oven and causing the smoke incident to the charging operation together with the gases contemporaneously generated in the oven to accumulate in the pockets lying between the lines of repose 12. The smoke and 65 gas which normally would be trapped and

would force their way out through the feed openings are by my invention conveyed by the passageways 11 in the bridge members 10, in substantial alignment with the top of the oven, through the curtains of descending material and hence along the top of the oven to the gas and smoke oftakes 4 from which they are led to appropriate separating mechanism or are otherwise disposed of at a point remote from the oven, all interference with the charging operation that would otherwise result from blowing out through the feed openings being successfully obviated.

Due to the position of the bridge members in the upper hot parts of the oven there is little tendency for the accumulation of carbon or other deposits in the bridging passageways but such accumulation as may exist is readily burned out by subjecting the passageways to the burning action of hot air passed through the oven after it has been emptied by the pusher and this action may be further facilitated if desired by removing the plugs 15 through the feed opening.

The invention as hereinabove set forth is embodied in a particular form of construction but may be variously embodied within the scope of the claims hereinafter made.

I claim:

1. In coke ovens, or the like, in combination; a heat treating chamber having a wall provided with a feed opening for delivering to the chamber the material to be heat treated and having smoke or gas pockets on opposite sides of said opening that open into said chamber; and means bridging said opening for conveying smoke and gases from one pocket to the other past a stream of material entering through said feed opening; substantially as specified.

2. In coke ovens, or the like, in combination: a heat treating chamber having a wall forming a top for said chamber and provided with a feed opening for delivering to the chamber the material to be heat treated and having smoke or gas pockets on opposite sides of said opening that open into said chamber; and means bridging said feed opening at its inner end and providing a path substantially in line with the top of the oven chamber for the smoke and gas from one pocket to the other past a stream of material entering through said feed opening; substantially as specified.

3. The combination as defined in claim 1, in which the bridging means is composed of refractory material; substantially as specified.

4. The combination as defined in claim 1, and in which the wall provided with a feed opening forms the roof of the oven and the top of said chamber and in which the bridging means is composed of brickwork with its opposite ends merged in the oven roof; substantially as specified.

5. In the combination as defined in claim 1, a brace member supporting the bridging means at a point intermediate the ends of the latter, said brace member being secured at one end to an oven wall; substantially as specified.
6. The combination as defined in claim 1, in which the bridging means is provided with a smoke and gas passageway extending at each end beyond the confines of said opening; substantially as specified.
7. The combination as defined by claim 2, in which the bridging means is provided with a straight elongated smoke and gas passageway open on its under side and extending at each end beyond the confines of said opening; substantially as specified.
8. The combination as defined in claim 1, in which the feed opening is countersunk around the bridging means to facilitate the feeding of material past said means; substantially as specified.
9. The combination as defined in claim 1, and in which the wall provided with a feed opening forms a top for said chamber and in which the feed opening is elongated at its lower end in a direction transverse of said bridging means to facilitate the feeding of material past the bridging means; substantially as specified.
10. The combination as defined in claim 1, in which plugs are provided in the bridging means removable to facilitate the cleaning out of carbon or other deposits; substantially as specified.
11. In coke ovens, or the like, in combination: a heat treating chamber having a wall forming a top for said chamber and provided with a feed opening for delivering to the chamber the material to be heat treated and having smoke or gas pockets on opposite sides of said opening that open into said chamber; said oven being provided with a central passageway on substantially the level of the top of said chamber for by-passing smoke and gas from one pocket to the other through a stream of material entering through said feed opening; substantially as specified.
12. In coke ovens, or the like, in combination: a heat treating chamber having a wall forming a top for said chamber and provided with a feed opening for delivering to the chamber the material to be heat treated and having smoke or gas pockets on opposite sides of said opening that open into said chamber; said oven being provided with a straight central passageway on substantially the level of the top of said chamber for by-passing smoke and gas from one pocket to the other through a stream of material entering through said feed opening; substantially as specified.
13. The combination as defined in claim 11, in which removable plugs positioned in the said central passageway between the feed opening and the by-pass passageway are em-
- ployed to facilitate, when removed, the cleaning out of carbon or other deposits in said passageway; substantially as specified.
14. In the combination as defined in claim 1, bracing means supporting the bridging means at a point intermediate the ends of the latter, said bracing means extending on opposite sides of said bridging means, the ends of said bracing means remote from the bridging means being secured to the oven structure; substantially as specified.
15. In coke ovens, or the like, in combination: a heat treating chamber having a wall provided with a feed opening therethrough and having smoke and gas pockets on opposite sides of said opening that open into said chamber; and a by-pass for smoke and gas within said feed opening adapted to convey said smoke and gas through said feed opening, and by-pass a stream of material fed through said opening, from one pocket to the other; substantially as specified.
16. In a horizontal coking retort oven battery, in combination: a coking chamber having a top wall forming the top of said chamber; heating walls therefor, on opposite sides of and contiguous to said coking chamber; gas offtakes extending transversely through said top at opposite ends of said chamber respectively and communicably connected with said coking chamber; said coking chamber having a plurality of fuel charging openings extending through its top wall, the charging openings for said chamber being arranged between said gas offtakes and spaced from each other and from said gas offtakes; and bridging means disposed within each of said charging openings, each of said bridging means being arranged in the respective charging openings so as to provide a path within their respective openings for passage of gas from the top of the chamber on one side thereof to the top of the chamber on the opposite side thereof while fuel is within and is being fed therethrough and each of said bridging means being adapted to maintain fuel within or being fed through their respective charging openings out of the paths in said openings for flow of gas from one side to the other thereof.
17. In a horizontal coking retort oven battery, in combination: a coking chamber having a top wall forming the top of said chamber; heating walls therefor, on opposite sides of and contiguous to said coking chamber; a gas offtake extending transversely through said top and communicably connected with said coking chamber, said coking chamber having a fuel charging opening extending through its top wall, the charging opening for said chamber being arranged between the opposite ends thereof and spaced from said gas offtake; and bridging means disposed within the said charging opening for said chamber, said bridging means being so ar-

ranged within the charging opening as to provide a path within said opening for passage of gas from the top of the chamber on one side of said opening to the top of the chamber on the opposite side thereof while fuel is within or is being charged through said opening, and being adapted to maintain said fuel in said opening out of the path in said opening for flow of gas from one side to the other thereof.

10 In testimony whereof, I have hereunto set my hand.

JOSEPH VAN ACKEREN.
